STAPLER

Herbert W. Marano, Summit, N. J., assignor to Wilson Jones Company, Chicago, Ill., a corporation of Massachusetts

Application April 27, 1954, Serial No. 30,219

Term of patent 14 years

(Cl. D74—1)

To all whom it may concern:

Be it known that I, Herbert W. Marano, a citizen of the United States and a resident of Summit, New Jersey, have invented a new, original, and ornamental Design for a Stapler, of which the following is a specification, reference being had to the accompanying drawing, forming a part hereof, in which

Figure 1 is a side elevational view of a stapler showing my new design, the base plate portion thereof which constitutes the essential feature of my design being shown in solid lines on the drawing;

I claim.

The ornamental design for a stapler, as shown and described.
